TRAVELING BAG

Frank J. Sullivan, Oshkosh, Wis.

Application June 6, 1934, Serial No. 729,168

2 Claims. (Cl. 190—41)

The present invention relates to improvements in the construction and operation of garment loading fixtures for traveling bags, and more especially for carriers of the Gladstone type, where in the closure sections may be swung into substantial end-to-end alinement when the case is opened.

An object of the invention is to provide an improved garment loading fixture for carrier cases, which is simple and compact in construction, and which is, moreover, highly effective in use.

It has heretofore been proposed to apply various types of garment loading fixtures to the interiors, and especially within the cover sections, of luggage carriers of the type wherein the cover is of less depth than the main section and is swingable into substantially vertical position with respect to the horizontal main section when the case is open. When but limited head room is available, it is difficult to load and to unload this prior type of luggage carrier, it being far more desirable under such conditions, to be able to swing the closure sections into substantially end-to-end, horizontal alinement when the case is open, as with an ordinary suitcase or Gladstone bag.

It is therefore a more specific object of the present invention to provide an improved garment loading fixture which is effectively cooperable with an ordinary traveling bag of the type wherein the closure sections are of substantially equal depth and may be swung open so as to occupy minimum head room, and which may be conveniently loaded and unloaded.

Another specific object of the invention is to provide an improved fixture for storing folded garments within a traveling case, which may be readily applied to standard carriers of various types.

Still another specific object of the invention is to provide improved mechanism for permitting removable attachment of a garment hanger or the like, to a support such as a garment folding frame.

A further specific object of the invention is to provide a garment folding and supporting structure which is rigid and strong in construction, which may be readily manipulated, and which may be manufactured at minimum cost.

These and other objects and advantages of the invention will be apparent from the following detailed description.

A clear conception of embodiments of the supposedly novel features, and of the construction and operation of fixtures built in accordance with the invention and adapted for cooperation with

both men's and ladies' garments, may be had by referring to the drawings accompanying and forming a part of this specification, in which like reference characters designate the same or similar parts in the various views.

Fig. 1 is a perspective view of an ordinary suitcase in open position, with one of the improved folding frames positioned preparatory to loading, and showing a single coat and trouser hanger associated with the frame;

Fig. 2 is a vertical section thru the open suitcase of Fig. 1, taken on the line 2—2 and showing the folding frame with two hangers associated therewith, in several operative positions in full and dot-and-dash lines;

Fig. 3 is a similar vertical section thru the closed suitcase, showing the frame with two hangers housed within one section of the case;

Fig. 4 is an enlarged fragmentary view of the pivoted frame mounting, of the hanger mounting, and of a fragment of the suitcase;

Fig. 5 is a similarly enlarged end view of the improved garment hanger mounting portion of the fixture;

Fig. 6 is a perspective view of the suitcase in open position, with one of the improved folding frames positioned preparatory to loading, and showing a single ladies' garment hanger in the form of a straight bar associated with the frame;

Fig. 7 is a vertical section thru the open suitcase of Fig. 6, taken on the line 7—7, and showing the folding frame with four hanger bars associated therewith, in several operative positions in full and dot-and-dash lines; and

Fig. 8 is a similar vertical section thru the closed suitcase, showing the frame with four hanger bars housed within one section of the case.

While the invention has been shown and described herein as being specifically applied to an ordinary Gladstone type of traveling bag, it is not desired to restrict the scope by such specific showing since some of the improved features are obviously more generally applicable.

Referring to the drawings, the traveling bag shown therein, and to which the improved fixtures have been applied, comprises in general a pair of leather closure sections 10, 11 of approximately the same size and depth, these sections being pivotally connected by a hinge 12 and being adapted to be swung open, as shown in Figs. 1, 2, 6, and 7, and to be closed, as shown in Figs. 3 and 8. The hinge 12 is part of a metal frame consisting of a part 13 secured to the closure section 10, and a part 14 secured to the section 11,

the latter frame part 14 being adapted to overlap the part 13 when the bag is closed and providing a support for the carrier handle 15. The portions of the frame parts 13, 14 adjacent to the handle 15 are provided with a latch 16 of usual construction, and the interiors of the sections 10, 11 are segregated from each other by a flap 17 which is pivotally attached to the frame part 14 near the hinge 12 and the edges of which are cooperable with flanges 18 formed integral with the frame parts and extending inwardly, as shown.

The improved men's garment folding and confining fixture specifically shown in Figs. 1-5 inclusive, comprises generally a metal U-shaped frame 19, the inner ends 20 of the side bars of which are bent as shown and are swingably connected to brackets 21 secured to the frame part 13, and the cross rod of which has a garment folding rod 22 secured thereto; and one or more garment hangers 23 detachably secured to supporting plates 24 attached to the offset frame ends 20. The special bent formation of the inner frame ends 20, besides providing clearance for a plurality of garment hangers and for the garments associated therewith when the frame 19 is swung into loading position, also causes the hanger supporting plates 24 to be carried as near as possible to the hinged side of the section 10 when the frame is disposed within this section, thereby permitting the loading of garments of maximum length without excessive folding thereof. As previously indicated, the brackets 21 are rigidly attached to the frame part 13 either at one end or at the sides, and have slots 25 with which the pivots 26 of the frame 19 are both rotatably and slidably cooperable in order to permit relatively thick garments 27 to be applied to the hangers 23 and folded within the section 10 without throwing undesirable strain on these pivots. The side bars of the frame 19 may be of any desired length not exceeding the limits of the opening in its confining section 13, and the folding rod 22 is preferably rounded in order to eliminate sharp creasing of the garments.

The supporting plates 24 are of special construction, as shown in detail in Figs. 4 and 5, each plate 24 being provided with several notches 28 adapted to directly receive the headed ends 29 of the hangers 23. A resilient confining plate 30 cooperates with each of the supporting plates 24 in the manner shown in Fig. 5 to frictionally and pivotally confine the substantially spherical hanger ends 29 within the notches 28 and to provide a snap action during insertion and removal of the hangers 23. The plates 24, 30 are of uniform width thru-out their lengths in order to insure the same clamping effect on all garment hangers and may be attached to the bent ends 20 of the loading and folding frame 19 by riveting or welding, being disposed at an angle to the plane of the frame 19 in order to provide proper clearance for the superimposed or adjacent hangers 23. Aside from the headed pivot ends 29, the hangers 23 are of relatively well-known construction, comprising a transverse upper bar 31, to the opposite ends of which the pivot ends 29 are directly attached, a coat hanger portion 32, and a trouser hanger bar 33, all of these parts ordinarily being formed of a single piece of wood or fiber. Obviously, as many of these hangers 23 may be utilized as there are series of notches 28 in the plates 24; and a complete garment loading fixture may also be mounted in the other closure section 11, if so desired. The formation of the

frame 19 with bent or offset end portions 20 to which the plates 24, 30 are directly attached, so as to permit the hangers 23 to lie alongside of each other while pointing toward the bar 22, is of great importance in permitting effective loading of a maximum number of relatively thick garments; and the successive loaded hangers 23 are independently swingable like the leaves of a book.

The improved ladies' garment folding and confining fixture specifically shown in Figs. 6, 7, and 8, is quite similar to that just described, and again comprises a metal U-shaped frame 19 having bent pivot ends 20 swingably connected to brackets 21; supporting plates 24 attached to the bent ends 20 of the frame 19; and garment hanger bars 23' removably associated with the notches 28 of the plates 24 by means of headed ends 29', in the manner previously described. The garment hanger bars are preferably formed of metal, and as many of these bars may be provided as there are sets of notches 28 provided in the supporting plates 29. It is also to be observed that the hanger bars 23' are interchangeable with the hangers 23, so that either or both of these types of garment hangers may be associated with a common supporting frame, at the will of the user.

Since the mode of use of the men's and ladies' traveling bags, and the improved fixtures, are generally similar, it will suffice to describe specifically the mode of use of the men's case. When it is desired to load the improved traveling bag with garments, the individual garments 27 may first be folded over a hanger 23 in an obvious manner, after which the headed ends 29 of this hanger may be inserted within the notches 28 of the side plates 24, while the frame 19 is disposed in the position shown in Fig. 1. Such insertion of the headed ends 29 of the hanger 23 will result in subsequent frictional retention of the hanger ends 29 within the notches 28 by the resilient plate 30, in the manner illustrated in Fig. 5. The garment folding frame 19 may then be swung upwardly about its pivots 26 to cause the garment 27, coacting with the hanger 23, to be folded about the folding bar 22. Continued swinging of the frame 19 about its pivots 26 will eventually cause the same to enter the closure section 10 and to conceal the garment 27, as well as the fixture, within this closure section 10. When the fixture has been thus swung within its carrier section, the notched plates 24 will be carried into close proximity with the adjacent wall of the section 10 by virtue of the bent end 20 of the frame 19. If the garment 27 is relatively thick, and tends to crowd against the adjacent wall of the section 10, the pivots 26 will slide along the slots 25 and will thus accommodate the thick garment 27. The bent portions 20 of the sides of the frame 19 also permit pivoting of this frame within the flange 18 of the section 10 and subsequent swinging of the frame 19 thru an arc of substantially one hundred and eighty degrees, without interfering with the flange. The inclination of the notched plates 24 will also provide proper clearance when a plurality of hangers 23 are utilized, and the division flap 17 between the sections 10, 11 prevents the frame 19 from swinging beyond horizontal position and into the section 11. When the fixture has been confined within the section 10, the closure section 11 is freely accessible for packing or unpacking, and the bag may be readily closed, as shown in Fig. 3, for subsequent transportation. If so desired, a

second garment carrying fixture may be applied within the closure section 11, and any number of notches may be provided in the side plates 24 to thereby permit folding and storage of any desired number of garments. The frame 19 is swingable thru an arc of substantially one hundred and eighty degrees and may, if desired, be completely removed from its carrier section 10, when the hangers 23 are removed, by merely distorting the sides of the frame sufficiently to withdraw the pivots 26 from within the slots 25. The resiliency of the side members of the frame 19 will ordinarily suffice to maintain the pivots 26 within the slots 25, while still permitting complete removal of the frame in the manner indicated.

From the foregoing description it will be apparent that the invention provides simple, compact, and readily manipulable garment folding and storage means, which may be applied to any standard suitcase. By virtue of the fact that the sections 10, 11 are swingable into substantially horizontal, end-to-end alignment when the bag is open, loading and unloading may be readily effected with minimum head room. The improved fixture may obviously be applied to any standard suitcase, and the hangers 23, 23' are interchangeable with each other, thus permitting the use of either or both types of these hangers with a common folding frame 19. The bent portions 20 of the frame 19 facilitate loading of thick garments such as coats having fur collars, and also enable packing of a maximum number of garments in minimum space without subjecting the hangers to excessive stress. The same type of detachable snap connection as is provided herein for the hangers 23, may also be applied between the frame ends and the brackets 21 in order to facilitate bodily removal of the frame 19 and the hangers carried thereby. The improved fixture has proven highly successful and practical in commercial use and can be manufactured and applied at relatively low cost.

It should be understood that it is not desired to limit the invention to the exact details of construction and to the precise mode of use herein

shown and described, for various modifications within the scope of the claims may occur to persons skilled in the art.

It is claimed and desired to secure by Letters Patent:

1. A traveling bag, comprising, hingedly connected sections swingable into end-to-end alignment, a garment folding frame having side arms provided with reversely bent ends and a transverse bar rigidly interconnecting the opposite arm ends, brackets secured to one of said sections adjacent the hinge connection thereof and means pivotally supporting said bent frame arm ends on said brackets, the bent ends of said frame arms being formed to clear the hinged walls of said sections and to position said bent arm portions a considerable distance above the upper ends of said walls when the bag is wide open and said frame has been swung over the other section in which position the reverse bend enables the side arms to lie parallel with said other section, and one or more garment hangers attachable directly to said bent arm portions remote from said bar.

2. A traveling bag, comprising, hingedly connected sections swingable into end-to-end alignment, a garment folding frame having side arms provided with reversely bent ends and a transverse bar rigidly interconnecting the opposite arm ends, brackets secured to one of said sections adjacent the hinge connection thereof and means pivotally supporting said bent frame arm ends on said brackets, a supporting plate secured to the bent end portion of each of said frame arms, the bent ends of said frame arms being formed to clear the hinged walls of said sections and to position said plates a considerable distance above the upper ends of said walls when the bag is wide open and said frame has been swung over the other section in which position the reverse bend enables the side arms to lie parallel with said other section, and one or more garment hangers attachable directly to said bent arm portions through said supporting plates.

FRANK J. SULLIVAN. 45
